UNITED STATES PATENT OFFICE.

CHARLES J. NASH, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-RIGGING.

1,109,005.

Specification of Letters Patent. Patented Sept. 1, 1914.

Application filed December 7, 1911. Serial No. 864,461.

To all whom it may concern:

Be it known that I, CHARLES J. NASH, a citizen of the United States, and resident of Chicago, county of Cook, and State of Illinois, have invented certain new and useful improvements in Draft-Rigging, of which the following is a specification, and which are illustrated in the accompanying drawings, forming a part thereof.

10 The invention relates to draft rigging for railway cars being particularly applicable to draft rigging of the type generally known as twin spring gears in which a pair of springs are located side by side, though 15 as to some of its features being applicable also to other types of gears.

The embodiment of the invention is fully described and is illustrated in the accompanying drawings in which—

20 Figure 1 is a plan section of the gear and some parts of a car; Fig. 2 is a transverse vertical section on the line 2—2 of Fig. 1; Fig. 3 is a transverse vertical section on the line 3—3 of Fig. 1; Fig. 4 is a detail in perspective of the spring spacing and retaining element; Fig. 5 is a longitudinal vertical sectional view on the line 5—5 of Fig. 1; Fig. 6 is a perspective view of the yoke, and Fig. 7 is a detail in perspective of the forward end of one of the cheek plate castings,

25 A pair of draft or center sills is shown at 10, 11 and at 12 there is represented a carry iron for supporting the coupler bar 13.

30 At 14, 15 there is shown a pair of springs arranged one above the other and located between the draft sills. There is also shown at 16, 17 a pair of smaller springs located respectively inside of the springs 14, 15. These springs are housed within the yoke generally designated by the numeral 18 and there shown as comprising a top member 19, a bottom member 20, a rear end 21 uniting the top and bottom members, and side plates 22, 23 uniting the top and bottom members at their forward ends. The side plates of the yoke constitute jaws between which the butt of the coupler 13 is received and to which it is secured by means of a key 24 passing through alined slots in the side plates of the yoke and in the butt of the coupler. Preferably, as shown, this key 24 is of sufficient length to extend through and project beyond the draft sills 10, 11 which are suitably slotted for its accommodation

and to allow of its horizontal travel with 55 the coupler bar.

The rear end 21 of the yoke is provided with integral lateral projections 25, 26 for engaging the rear draft lugs of the cheek plates and hence constituting the rearward 60 follower through which the buffing stresses are transmitted to the draft sills. The forward follower 27 is a separate plate inclosed between the top and bottom members of the yoke and engaging the forward draft lugs 65 of the cheek plates for transmitting to the sills the pulling stresses.

The inner faces of the top and bottom members 19 and 20 of the yoke are concave to provide seats for the springs 14, 15. The 70 spring spacing and retaining element generally designated by the numeral 28 is formed of a steel plate 28 having a plurality, as shown two, of slits extending inwardly from its side edges thereby providing a plurality of tongues, as 29, 30, 31, 32, 33, 34. Some of the tongues at each side of the plate are bent upwardly and some downwardly to conform to and engage the peripheries of the springs. As shown, the two 75 outer tongues at each side are bent downward and the center tongue is bent upward. The parts are so proportioned that when assembled the springs, while being free to expand and contract, are held against lateral 80 displacement from the yoke.

In assembling the parts the follower 27 is first placed in the yoke, one of the springs is now placed within the yoke, the spacing and retaining element, with its tongues at 90 one side properly curved, one or a pair of tongues at its opposite side remaining straight, is inserted, the spring is rolled laterally beyond its normal position to permit the companion spring to be inserted, the two 95 are then brought into their proper position within the yoke and the remaining tongue or pair of tongues bent as by a blow from a hammer to curve it to the periphery of the spring last inserted, thereby forming the lock for retaining the springs in place. As the springs are somewhat compressed when placed in the yoke they constantly react against the forward and rear follower and the rigging thus formed is therefore intact and can be handled as a single piece, the forward follower being held against the inner ends of the side plates 22, 23 of the yoke.

The length of the retaining element is less than the range of travel of the followers so that it does not sustain any of the burden incident to either buffing or pulling stresses.

5 The cheek plates 35, 36 are riveted to the sills. Each is provided with a rear stop shoulder 37 for engagement by the rear follower and a forward stop shoulder 38 for engagement by the forward follower, and 10 also with an intermediate shoulder 39, 40 for limiting the forward movement of the rear follower and the rearward movement of the forward follower. The cheek plates extend forwardly beyond the apertures in the sills which accommodate the key 24 and are 15 themselves apertured, as shown at 41 to receive the key, the aperture of each being surrounded by an outstanding flange 42 which enters the sill aperture as a bushing. The 20 aperture of each cheek plate is also surrounded by an instanding flange 43, which, as shown, is lower at its rearward than at its forward end. A flange 44 extends forwardly from the outer edge of the shoulder 25 38 and at its central portion is connected with the flange 43 which braces and greatly strengthens the shoulder.

A carry iron 45 is bridged across between the sills 10, 11 passing under and supporting the draft rigging, the yoke sliding thereon. This carry iron is detachably connected with the sills by means of bolts and is applied after the rigging has been raised to its proper position.

35 While I have shown and described a preferred form of construction embodying the various features of my invention, it will be understood that I do not limit myself thereto as various changes can be made without departing from the scope of the invention; as for example, while the inner faces of the top and bottom members of the yoke are shown as concave it is essential only, for the purpose of holding the springs in place, 40 that these members be provided with instanding projections or flanges at or adjacent their edges.

The key 24 which secures the coupler bar

to the yoke is permitted a longitudinal movement with reference to one of these members in order that the coupler bar may move inward under buffing stresses, the yoke remaining stationary as its rearward end is engaged directly with the buffing shoulders 37. As shown, this movement of the key 55 is with reference to the yoke, the apertures in the side plates 22, 23, being elongated for this purpose.

I claim as my invention—

1. In a draft rigging, in combination, a 60 yoke having laterally projecting shoulders for engaging draft lugs, whereby longitudinal pressure on the yoke exerted by the resilient element carried therein will bring it to central position.

2. In a draft rigging, in combination, a 65 yoke having longitudinal members with concave inner faces, a pair of springs located side by side and one seated against the inner face of each of such members, and a 70 spacing and locking element interposed between the springs and having laterally projecting tongues at each side engaging the two springs.

3. In a draft rigging, in combination, a 75 yoke having longitudinal members each having instanding marginal edges, a pair of springs located side by side and one seated against the inner face of each of such members, and a spacing and locking element interposed between the springs and having laterally projecting tongues at each side engaging the two springs.

4. In a draft rigging, in combination, a 80 pair of springs located side by side, and a 85 spacing and locking element, located between the springs, formed of a plate of pliable metal slitted from each side edge to form a plurality of tongues adapted to be bent to conform to the curve of the peripheries of the springs.

CHARLES J. NASH.
